J. B. LADD

CENTRIFUGAL CASTING MECHANISM

Filed Dec. 29, 1922

Patented Apr. 1, 1924.

1,489,036

UNITED STATES PATENT OFFICE.

JAMES B. LADD, OF ARDMORE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

CENTRIFUGAL CASTING MECHANISM.

Application filed December 29, 1922. Serial No. 609,550.

To all whom it may concern:

Be it known that I, JAMES B. LADD, a citizen of the United States of America, and resident of Ardmore, in the county of Montgomery, in the State of Pennsylvania, have invented certain new and useful Improvements in Centrifugal Casting Mechanism, of which the following is a true and exact description, reference being had to the accompanying drawings, which form a part thereof.

My invention relates to centrifugal casting mechanism and particularly to mechanism where a core supporting ring is to be detachably secured in the end of the mold so as to support a core during the casting operation. The object of my invention is to provide an improved appliance for securing this core ring in position during the casting operation. A further object of my invention is to provide, in connection with latching mechanism to be described, a driving device such as a pulley by which power can be applied to the mold for rotating it.

The nature of my improvements will be best understood as described in connection with the drawings in which they are illustrated and in which—

Figure 1 is a sectional elevation of one end of a casting apparatus adapted for casting a bell ended pipe.

Figure 2 is a cross section on the line 2—2 of Fig. 1.

Figure 3, a sectional view on the line 3—3 of Fig. 2, and

Figure 4 is a view generally similar to the construction shown in Fig. 1 but showing a core ring adapted to support a solid metallic core piece instead of the sand core indicated in Fig. 1.

The construction of the metallic core indicated in Fig. 4 is also my invention and forms the subject matter of my co-pending application.

A indicates the casing of the casting machine which serves also as a water jacket for the mold. B is the mold having a bell mouth indicated at B', a laterally projecting flange indicated at B², an outwardly projecting perforated ring indicated at B³ and a core ring seat indicated at B⁴. C is the core ring having a seat portion which fits in the conical seat formed at the end of the mold, this core ring having, as shown, an

annular conical surface C' extending beyond the outer surface of the flange B². D, D, are latches having tapered ends which extend through the perforations in the ring B³ and fit against the latch receiving surface C' of the core ring. These latches are formed with projecting pins, as indicated at D'. E, E, indicate packing between the flange B² and the casing A. F indicates a sand core supported on the core ring C.

In the modification illustrated in Fig. 4, an annular metal core piece indicated at f is supported on the core ring here indicated at c, this core being at its inner end divided into tongues f' by longitudinal slots, also supported on the ring f is a ring G having a series of tongues indicated at G' projecting toward the core ring and a thin metal shell indicated at H is supported on the tongues f' and G', as shown. This special construction forms the subject matter of my co-pending application referred to above and is only shown here as indicating that the core ring may support a metal core as an alternative to a sand core.

J indicates the end of a runner by which molten iron is run into the mold. K is an annular plate secured to the flange B² of the mold as by screws indicated at L, this plate having a crowned surface indicated at K' connected with its outer rim and an annular preferably upwardly flared ring K² connected with its inner edge. As shown, annular seats K³ are formed in the plate K connecting with slots K⁴ which run in radial directions and in which lie the latches D. M, M, indicate annular shells adapted to be seated in the seats K³, as shown, having upwardly extending portions indicated at M' and, as shown, grooves M². N indicates a pivot pin secured in the shell M, as shown, and on which is pivoted a latch lever O having a counterweighted outer end O' and a forked inner end O² which engages the pins D' extending laterally from the latches D. P is a spring acting on the latch lever O, as shown, so as to normally press the latches inward. Q, Q, are locking blocks having flanges which fit into the slot M² of the shell M, the blocks being held in place by screws indicated at Q'.

In operation the latches are normally pressed inward by the action of the spring P which, however, does not exert a force

which makes it difficult to push the latches away in inserting the core ring or in withdrawing the core ring. When the mold is rotated the centrifugal force exerted by the projecting ends O' of the latch levers O presses the latches in with increasing force making it entirely sure that the core rings and cores supported on the rings shall not be displaced during the casting operation.

10 Having now described my invention, what I claim as new and desire to secure by Letters Patent, is:

1. A centrifugal mold having at its end a seat for a core ring in combination with latches secured to the mold for locking the core ring in its seat and counterweighted latch actuating fingers attached to the mold and operating to press the latches in against the core ring with increasing force as the 20 rotative speed of the mold increases.

2. A centrifugal mold having at its end a conical seat for a core ring in combination with a core ring having a conical seat adapted to fit in the seat in the mold and outer latch engaging surfaces, latches secured to the mold for locking the core ring in its seat by a wedging action and counterweighted latch actuating fingers attached to the mold and operating to press the latches in against the core ring with increasing force as the 20 rotative speed of the mold increases.

3. A centrifugal mold having at its end a seat for a core ring, in combination with

a driving pulley secured to the end of the mold and having an internal opening larger 35 in diameter than the greater diameter of the core ring seat, latches for securing the core ring in its seat radially movable at the end of the mold and counterweighted latch 40 actuating fingers pivotally connected to the pulley and acting to press the latches inward with increasing force as the speed of rotation increases.

4. A centrifugal mold having at its end a seat for a core ring in combination with latches secured to the mold for locking the core ring in its seat, counterweighted latch 45 actuating fingers attached to the mold and operating to press the latches in against the core ring with increasing force as the 50 rotative speed of the mold increases and springs acting on the fingers to press them inward.

5. A centrifugal mold having at its end a seat for a core ring, in combination with a driving pulley secured to the end of the mold and having an internal opening larger 55 in diameter than the greater diameter of the core ring seat, and of conical shape, latches for securing the core ring in its seat radially movable at the end of the mold and counterweighted latch 60 actuating fingers pivotally connected to the pulley and acting to press the latches inward with increasing force as the speed of rotation increases.

JAMES B. LADD.
